AND ONE-THIRD TO MARY B. OAKES, BOTH OF NEW YORK, N. Y.

CARBURETING DEVICE FOR CALORIC MOTORS

Application filed February 26, 1927. Serial No. 171,202.

My present invention relates to fuel forming devices for internal combustion engines and other devices, and while it is herein directed to an improvement in carburetors, it 5 contemplates a means for the further treatment in such fuels after they have left any carbureting or vaporizing device, whereby to improve the texture of the vaporous fuel, to remove surplus liquid fuel condensation 10 therefrom and generally to create a homogeneous, readily ignitable vapor.

Another advantage of my improvement relates to means whereby the fuel vapor is subjected to a restrictive, squeezing action, 15 in its passage through the apparatus, thereby to preserve the desirable nature of the fuel so produced.

Another object is to provide heating means for the fuel vapors passing to the 20 cylinders, to maintain their integrity as such, and to permit the use of various grades of liquid fuels and distillates for forming explosive fuel mixtures.

The foregoing is accomplished in part 25 by the provision of a valved inlet passage from the usual carburetor to the manifold and thence to the engine cylinders, in which passage, attenuation of the moving vapor stream is effected by constricting the stream, 30 over a long distance and between large areas of wall surface, preferably heated, in which passage fuel condensed to liquid is substantially squeezed out of the vapor stream and returned to the carbureting point, there to 35 be again subject to the carbureting or vaporizing action of incoming air.

Another object of the invention is to provide a throttle means which permits control 40 of the fuel intake or complete throttling thereof, and further permits, when desired, a variable air inlet to the manifold for cooling the engine, coasting without fuel wastage, and at times to permit the engine to drift or run under its own momentum, sub- 45 substantially unconstricted as to the volume of pure air freely admitted to the cylinders to the entire exclusion of fuel and consequent power cycles, but to permit ready and immediate change to power cycle by throttle 50 manipulation of said means and without

throttle manipulation of the supply of fuel by the carburetor throttle.

This is in part accomplished by the provision of a member having a passage adapted to connect the carburetor intake with the engine manifold and having a fuel valve therein between said passage and intake. A drift valve connects said passage to the exterior air; and means are provided which in one position hold the fuel valve open and the drift valve closed, in another position hold the drift valve open and the fuel closed, and when in an intermediate position hold both valves closed.

These and other capabilities will be disclosed as the description proceeds, and I do not desire to be held to the structural details hereof, as obvious modifications may be made without departing from the scope of the appended claims.

In the drawings:

Fig. 1 is a sectional view of the complete vaporizer with the fuel valve partially throttled and the drifting valve closed;

Fig. 2 is a fragmentary sectional view of the upper portion of the vaporizer fuel and air valves closed; and

Fig. 3 is a view similar to Fig. 2, showing complete gas throttle with air valve wide open.

In all of the foregoing views, a single manually operated indicator means controls the device from full power cycle through any degree of power throttle to full closure or throttle of the engine and thence to full air valve opening.

In the structure herein disclosed it is understood that the principal elements thereof are substantially cylindrical, and that the sections herein shown are substantially axial in each of the views.

My device is shown in combination with a capped fuel reservoir 1 having the usual float 2 pivoted as at 3 to actuate a fuel needle valve 4, which in turn closes the liquid fuel inlet 5, in the usual manner. This mechanism controls to keep the reservoir fuel at about the level of the line A-B. A fuel nozzle 6 having a manual fuel regulating needle 7 is suitably located in the carburetor

intake 8, which is for convenience here shown in the form of an elbow. The structure just described is of usual construction, and it is thought that no further description is necessary.

5 The carburetor intake port 8 has an upward extension 9 which is operably mounted on a fuel stream attenuating device 10 which comprises a suitable outer casing 11 having top and bottom closures 12, 13 and which in turn encloses a cylindrical fuel condensing chamber 14 which has hemispherical ends and is ported at the bottom, as at 15, where it joins the extension 9. The upper end of 10 this chamber is ported, as at 16, where it joins to a suitable gland member 17 on the closure 12 and in turn has a lateral port 17' which may form part of the customary fuel intake manifold of a gas engine.

20 The outer casing 11 is provided with suitable inlets such as 18 and 19 whereby hot water from the engine or exhaust gas therefrom may be led into the casing 10 thereby effectually heating the walls of the chamber 14 to any desired or controlled degree.

30 The upper part of the member 17 generally denoted by 20 is constructed to form a preferably upstanding duct or bore in which is reciprocably mounted a valve stem 21 the upper end of which has suitably affixed thereto a spring thrust collar 22, said valve stem projecting downwardly through the bored shoulder 23 which forms part of the closure wall of the outlet port 17'. Between 35 this shoulder 23 and the collar 22 is compressed a helical spring 24.

40 On the lower end of the stem 21 is affixed a reciprocable controlling valve 25, somewhat ovate in form, having preferably straight cylindrical walls and hemispherical ends. For convenience in operating, this valve may be preferably hollow.

45 The valve 25 may be caused to move to occupy a mid-position in the chamber 14, thereby permitting fuel gas from the carbureting point to flow between the inner walls of the chamber 14 and outer walls of the valve 25 in such a manner as to cause a partial expansion of this upflowing vapor 50 due to the formation of the upper and lower ends of chamber 14 and valve 25. The path of the vapor is generally indicated by the arrows in this view.

55 Means for manipulating this valve for full opening or full closure or intermediate positions will now be described. At the upper end of the upstanding part 20 is provided an offset bracket 26 provided with a pivotal point 27 and to which is fulcrumed an operating lever 28 in contact with the under side of which and the duct 20 there is arranged an extension 29 of the valve stem 21, so that a relatively upward and downward movement of the lever 28 may cause the valve 25 to be moved up or down, by either

the spring 24 or the lever according to the direction of the operation.

To the free end of the lever 28 another pivotal joint 30 is provided to which is pivotally attached a link 31, this in turn being attached to a pivotal connection 32 on the end of a controlled bell crank 33 which is L-shaped and has a manual control handle 26 and is pivoted at 34 to cooperate with a graduated sector or scale 36. Manipulation of the handle with its indicating needle 37, as will be seen from other views herein, causes the lever 28 to be raised or lowered against the tension of the spring 24 thereby causing the valve 25 to assume any desired throttling position. Cooperating parts illustrating the means embodying the sector 36 will be understood and it is not thought necessary that these be illustrated in detail as they may be located in any desired position.

Substantially midway of the lever 28 is located a bored yoke 38 (Fig. 1) through the bore of which is loosely passed for free movement, an upstanding drift-valve stem 39, the upper end of which is provided with a threaded adjusting nut 40 whereby the stem may be adjusted for lifting contact to operate the stem 39 at any desired position of angular movement of the valve lever 28.

55 Lateral to the member 17 and communicating with the port 16 is a drift valve connection 41 which has an upstanding perforated air inlet portion or valve housing 42 capped with a suitable cap 43 having a bore therein to receive the valve stem 39 at the lower end of which is mounted a valve 44 covering an air inlet valve seat 45. Between the under side of the cap 43 and the top of the valve 44 is a tension spring 46 which tends to normally keep the air or drift valve upon its seat.

60 When the controlling lever 33 is moved rightwardly, it will cause the valve 25 to be moved up thereby closing the fuel inlet within the chamber 14 as indicated at Fig. 2, thereby to throttle the fuel inlet and in consequence, the motor will naturally be caused to stop due to the complete throttling of the intake from the carburetor.

65 Further movement of the handle 35 to the right will cause the lever 28 to be lifted upwardly thereby lifting the valve stem 39 and its attached valve 44 thereby pressing the valve spring 46 upwardly, opening the air valve seat 45 and admitting air into the inlet port 16 by reason of the holes 47, as indicated by the arrows in Fig. 3.

70 If the control lever 33 is set as shown in Fig. 3 only inertia will cause the engine to stop since there is no incoming charge of fuel; and in case of coasting in a gas engine driven automobile, my device permits the coasting of the engine and vehicle without disconnecting the engine from the vehicle.

by release of the clutch. Change from power cycle as indicated in Fig. 1 may be practically instantly made by a quick move of the control handle 35 and there need be no manipulation of either the spark or the clutch in order to discontinue the power cycle of the engine without declutching as above described.

One obvious advantage of my construction is that it permits the admission of atmospheric air to the cylinders, whereby the engine may be cooled on a long coast.

Another advantage is obvious from the fact that, as in the case of the carburetor valve control 25, the drift valve mechanism may be also varied in its position from fuel open throttle to closed throttle as illustrated in Fig. 2 where both valves are against their respective seats and therefore will cause the engine to stop.

Another advantage of my device is that any change from full power cycle to full drift cycle may be readily made without attention to the other operative controls of the engine, and when so made, an instant change, from full drift position to full wide open gas throttle position may be made, and a gradual pick-up of the engine cycle be accomplished without the tendency to backfire in preceding charges of fuel mixture that may have passed through the muffler of the engine.

Another advantage is that the instant of the return from position in Fig. 3 to the position shown in Fig. 1, the incoming gas mixture is started through the engine. Incidentally ignition of the incoming charge occurs just as soon as such charge reaches the cylinders in proper firing condition or mixture.

Due to the general structure of the control mechanism, there is an added advantage in the ability to create by my apparatus homogeneous unitary gases or vaporized mixtures of explosive fuel which will be substantially without large globules as it reaches the cylinders. This is due to

First. The heat of the large area of the wall 14 surrounding the valve 25,

Second. The increased diameter of the valve chamber 14' over the carburetor duct 9, and

Third. The comparatively large area of the valve 25 within the chamber 14', which causes the incoming gases from the carburetor C to be virtually expanded in their forward travel and then constricted by the tapering aperture 25' which is formed between the upper wall of valve 25 and the upper wall of the chamber 14.

Due to this particular action and the heat of the walls 14, it is virtually impossible for anything but a true homogeneous vapor mixture to reach the engine cylinders by way of the port 16; and any excess moisture or any

unvaporized or condensed liquid fuel will be turned into vapor through the heated walls of the chamber 14 or will fall back to be met again by the incoming fuel stream to be vaporized. It is therefore obvious that the fuel bearing stream from the carburetor is "wire-drawn" and due to the constricted orifice 25' and due to this attenuation of the gas stream the tendency is to squeeze out all surplus liquid fuel and to carry forward only a true vaporized or gaseous mixture for ignition purposes.

I claim as my invention:

1. In combination, a member having a passage from a carburetor outlet to a manifold; a yieldably closed inwardly opening fuel valve between said passage and intake; a stem connected to said valve; said member having a duct to said passage and a yieldably closed outwardly opening drift valve opening to the exterior air; a lever fulcrumed at one end on said member and having a hole through the lever, said lever engaging a stem secured to said drift valve and extending loosely through said hole; and a nut on said stem adapted to be raised by the lever to open the drift valve; said lever when in one position holding the fuel valve open and permitting the drift valve to close, when in another position opening the drift valve and permitting the fuel valve to close, when in an intermediate position, permitting both valves to close.

2. In combination, a member having a passage from a carburetor outlet to a manifold; a yieldably closed inwardly opening fuel valve between said passage and intake; a stem connected to said valve; a lever engaging the end of the stem; a body having a duct to said passage at the manifold side of said valve, and a valve opening having an outer seat; a yieldably closed drift valve on said seat; and a stem loosely connecting said valve and lever; said lever when in one position holding the fuel valve open and permitting the drift valve to close, when in another position opening the drift valve and permitting the fuel valve to close, when in an intermediate position, permitting both valves to close.

3. In combination, a member having a passage from a carburetor outlet to a manifold; a yieldably closed fuel valve between said passage and intake; a stem connected to the valve; a lever pivoted at one end on said member and engaging the end of the stem and provided between said stem and its free end with a transverse hole; a drift valve body laterally extending from said member and having a duct communicating with said passage, an upturned ventilated spring housing, a valve opening between said duct and housing and an outer seat around the valve opening; a cap on said housing; a drift valve on said seat; a spring between said cap and

valve; a stem secured to said valve and extending loosely through said hole; and a nut on said stem adapted to be raised by the lever to open the drift valve.

4. The combination with the intake manifold of an internal combustion engine and the outlet port of a carburetor, of a fuel valve arranged between said outlet port and manifold and normally closed, a passage 10 operating between said fuel valve and manifold, an air valve communicating with said passage and normally closed, and operating means cooperating with said fuel and air valves, said means when moved to one position opening said fuel valve and permitting said air valve to remain closed, when moved to a second position opening said air valve and permitting said fuel valve to remain closed, and when moved to a third position 15 permitting both said valves to remain closed.

5. The combination with the intake manifold of an internal combustion engine and the outlet port of a carburetor, of a fuel valve chamber having a port at one end 20 thereof communicating with said carburetor outlet port and having at its opposite end a valve port, means for communication between said valve port and intake manifold, a valve member in said valve chamber for co- 25 operating with said valve port and adapted for confining the fuel for substantially the whole length of the passage of the fuel through said chamber, said valve member normally closing said valve port, an air 30 valve discharging into said means for communication between said fuel valve port and intake manifold and normally closed, and operating means cooperating with said fuel and air valves, said operating means when 35 moved to one position opening said fuel valve and permitting said air valve to remain closed, when moved to a second position opening said air valve, and permitting said fuel valve to remain closed, and when 40 moved to a third position permitting both said valves to remain closed.

45 6. The combination with the intake manifold of an internal combustion engine and the outlet port of a carburetor, of a straight sided substantially oval fuel valve chamber having a port at one end thereof communicating with said carburetor outlet port and having at its opposite end a valve port, means for communication between said valve 50 port and intake manifold, a straight sided substantially oval valve member in said valve chamber for cooperating with said valve port, the parallel sides of said valve member for substantially the whole length of 55 the sides being spaced slightly away from the parallel sides of said chamber for confining the fuel passing through said chamber from said intake port to said valve port, said valve member normally closing said 60 valve port, an air valve discharging into 65

said means for communication between said fuel valve port and intake manifold and normally closed, and operating means cooperating with said fuel and air valves, said operating means when moved to one position 70 opening said fuel valve and permitting said air valve to remain closed, when moved to a second position opening said air valve and permitting said fuel valve to remain closed, and when moved to a third position permitting both said valves to remain closed. 75

7. In a device of the character described, a structure arranged between a carburetor outlet and an internal combustion engine intake manifold, said structure including a fuel valve normally closed, means for communication between said fuel valve and intake manifold, an air valve discharging into said means for communication and normally closed, and operating means cooperating with said fuel and air valves and including a handle, said operating means, when said handle is in one position, holding said fuel valve open and permitting said air valve to remain closed, said operating means, when said handle is in a second position, holding said air valve open and permitting said fuel valve to remain closed, said operating means, when said handle is in a third position, permitting both said valves to remain closed. 80 85 90 95

8. In a device of the character described, a structure arranged between a carburetor outlet and an internal combustion engine intake manifold, said structure including a fuel valve normally closed, means for communication between said fuel valve and intake manifold, an air valve discharging into said means for communication and normally closed, and operating means including a handle carrying a needle movable with the handle and cooperating with a dial for indicating the amount of movement of said handle, said operating means, when said handle is in one position, holding said fuel valve open and permitting said air valve to remain closed, said operating means, when said handle is in a second position, holding said air valve open and permitting said fuel valve to remain closed, said operating means, when said handle is in a third position, permitting both said valves to remain closed. 100 105 110 115

Signed at New York, in the county of New York and State of New York, this 29th day of January, A. D. 1927.
